CLAIM

The ornamental design for a satellite communication terminal, as shown and described.

DESCRIPTION

FIG. 1 is a top left front perspective view of a satellite communication terminal;

FIG. 2 is a left side view thereof;

FIG. 3 is a right side view thereof;

FIG. 4 is a rear side view thereof;

FIG. 5 is a front side view thereof;

FIG. 6 is a top view thereof;

FIG. 7 is a bottom view thereof; and,

FIG. 8 is a bottom left front perspective view thereof.
